UNITED STATES PATENT OFFICE.

EDMUND B. LENNIG, OF SAN FRANCISCO, CALIFORNIA, ASSIGNOR TO THERMIC ENGINEERING CO., OF SAN FRANCISCO, CALIFORNIA, A CORPORATION OF CALIFORNIA.

THERMOSTAT.

1,420,659.

Specification of Letters Patent. Patented June 27, 1922.

Application filed August 16, 1917. Serial No. 186,568.

To all whom it may concern:

Be it known that I, EDMUND B. LENNIG, a citizen of the United States, residing at San Francisco, county of San Francisco, State of California, have invented a new and useful Thermostat, of which the following is a specification.

My invention relates to a novel thermostatic device comprising a novel and unique 10 thermostat blade formed by annealing together two metal bodies of different mass and alloy to form a concrete unit, novel means being provided to effect the mounting of the thermostat blade and the supporting 15 member carrying the adjustable contact fixedly in relation to each other on a stationary element.

A further object of my invention is to 20 provide a novel thermostatic device of this character to control electrical devices in or out of thermal communication with the thermostat, when plugs are used for connecting electric devices.

A further object of my invention is to 25 provide a thermostatic device of such character that the same may be attached to any electric device using a plug connection by arranging one side of a terminal so that a complete circuit of electric energy will be 30 obtained in the thermostat.

My invention further consists of a novel manner of mounting and collocating said thermostat blade and its adjuncts whereby 35 a novel device of great utility is produced, as will be hereinafter described and pointed out in the claims.

For the purpose of illustrating my invention I have shown in the accompanying drawings one form thereof which is at present preferred by me since the same will be 40 found in practice to give satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a side elevation of an 50 electric iron with a thermostat embodying my invention attached thereto.

Figure 2 represents a rear view of the iron seen in Figure 1 showing the thermostat attached thereto.

Figure 3 represents a section on line 3—3 55 of Figure 1.

Figure 4 represents a section on line 4—4 60 of Figure 1.

Figure 5 represents a section on line 5—5 65 of Figure 6.

Figure 6 represents a section on line 6—6 70 Figure 2.

Figure 7 represents a rear view of Figure 6 with the thermostat casing removed showing an opening in communication with the 65 interior of the electric iron.

Similar numerals of reference indicate corresponding parts in the figures.

Referring to the drawings,

1 designates the shell, casing or body of an 70 electric iron inclosing the heating coils 22 seen in Figure 4 which may be of any suitable form or construction.

2 and 3 designate terminals for the connection of a plug and cord for the conveying 75 of electric current. 4 designates a base composed of insulating material upon which are mounted the terminals 5 and 6.

It will be understood from Figure 4 that the terminal 5 is attached to the terminal 2 80 and held in position by screws 20 and in contact with the metal plate 11 for the conveying of electric energy to the contact point 12 thence to contact point 14 to post 15 and metal strip 16, as will be best understood from Figure 3. The terminal 6 is held 85 in position by a screw 20 against the insulating block 4 and in contact with the metal strip 16 and in connection with the coil 22 by the wire or metal 21.

7 designates the casing inclosing the thermostatic blade composed of the members 10 and 10^x which as will be understood from the sectional view in the upper portion of Figure 3 are of different mass and alloy. 90

8 designates screws which hold the base 9 composed of insulating material in place within the casing 7. 11 designates a metal strip to which is fastened the thermostatic blade composed of the members 10 and 10^x 100 by means of screws 11^x; said metal strip 11 being in contact with the terminal 5 as will be understood from Figure 3.

12 designates a contact point on the thermostatic blade composed of the members 10 and 10^x there being a slight space at 13 formed when desired by the adjusting of the screw 14 which affects the adjustment of the travel 105

of the thermostatic blades 10 and 10^x for different temperatures.

15 designates a post fastened to the metallic member 16 and tapped for the adjusting screw 14, it being apparent that the terminal 6 is in contact with the metal plate 16.

17 designates a hole in the casing 7 of the thermostat to allow for the adjusting of the screw 14. 18 designates holes in the casing 7 to permit of the insertion of screws to hold the thermostat in position upon the shell 1 of the electric iron.

19 designates an opening in the casing 1 of the electric iron for the communication of the heat of the iron direct to the thermostatic blades 10—10^x.

20 designates screws holding the parts 5, 6, 3 and 2 in assembled position and for conveying the electric current.

The operation is as follows:—

The thermostat blade composed of the members 10 and 10^x of different mass and alloy is normally in an operative position 25 with respect to the contacts 12 and 14.

Under the influence of heat the thermostatic blade composed of the members 10 and 10^x will slightly bow by expansion so as to break the circuit 21 thus deenergizing 30 the coil 22, it being apparent that when the electric device cools it will cause the thermostatic blade composed of the members 10—10^x to contract and thus bring in contact the points 12 and 14 which energize the 35 coil 22.

It will be understood that my novel device is operative under or susceptible to either heat or cold and that it is very sensitive and quickly responds to any change of 40 temperature according to requirements the two bodies constituting my thermostat having different co-efficients of expansion and it is furthermore adjustable to different temperatures.

45 I desire to call special attention to my novel construction of the terminals of the iron or other similar electric device where a plug and terminals are used for the conveying of electric current to the thermostatic 50 device and it will be understood by those skilled in the art that the foregoing arrangement is but one manner of using my novel thermostatic device as the same may be utilized in various ways and in connection with numerous other electrical or other mechanisms, as will be apparent to those

skilled in the art. While I have shown my invention, in the present instance, as particularly applicable to the control of an electric sad iron, it will be understood that I do not desire to be limited in every instance to its application to a sad iron since there are many other electrical devices such as cookers, toasters and the like to which my invention is applicable, the same in its broad aspects being capable of being readily attached at a point between the plug and the heating elements irrespective of the use the device itself may be put to whether for ironing, heating, cooking, toasting or the like. 70

In the present instance, I have modified the electric iron by using two more terminals than are now ordinarily used and I break the circuit of the electric current by causing the same to pass through the thermostat instead of directly to the heating coil of the iron or other device and while I have shown a curved thermostatic blade as being employed it will be obvious that the contour of the blade may be varied according to requirements. 75

Having thus described my invention, what I claim as new and desire to secure by Letters Patent, is:—

1. In a device of the character stated, a 85 body, a plate of insulating material secured thereto, terminals mounted on said plate and projecting outwardly from said body, a thermostatic blade casing attached to said body and receiving the ends of said terminals, and a thermostat blade in said casing formed of U-shape and having one of its limbs attached to a fixed support and its other limb coacting with an adjusting device. 95

2. In a device of the character stated, a body, a plate of insulating material carried by the interior of said body, terminals mounted on said plate and projecting outwardly from said body, a thermostatic blade casing attached to said body and receiving the ends of said terminals, and a thermostat blade in said casing extending transversely to the axis of said body and having one of its limbs attached to a fixed support and its other limb coacting with a vertically adjustable contact depending from the top of the thermostat casing. 100 105

EDMUND B. LENNIG.

Witness:

GEO. PECK.
